UNITED STATES PATENT OFFICE.

FRANK ZAGMESTER, OF LA SALLE, NEW YORK.

SHIP'S TABLE.

1,244,158.

Specification of Letters Patent. Patented Oct. 23, 1917.

Application filed June 1, 1917. Serial No. 172,182.

To all whom it may concern:

Be it known that I, FRANK ZAGMESTER, a subject of the King of Hungary, residing at La Salle, in the county of Niagara 5 and State of New York, have invented certain new and useful Improvements in Ships' Tables, of which the following is a specification.

This invention relates to certain new and 10 useful improvements in ships' tables.

The primary object of the present invention is to provide a ship's table that is adapted at all times to assume a horizontal position where the ship is traveling in a true 15 horizontal course or rocking or shifting in other directions caused by waves.

A further object of the invention is to provide a ship's table capable of assuming a horizontal position at all times regardless 20 of the relative position of the ship deck for supporting the same and embodying means adapted to hold the same stationary with respect to its supporting base.

With these general objects in view and 25 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—

35 Figure 1 is a vertical sectional view of a ship's table constructed in accordance with the present invention showing the table base and weighted top movably mounted therein with the shiftable means for holding 40 the table top stationary with respect to the supporting base, the shiftable means being disengaged from the table top.

Fig. 2 is a horizontal sectional view taken on line II—II of Fig. 1 showing the manner of supporting the table top upon its base for universal movement.

45 Fig. 3 is a horizontal sectional view taken on line III—III of Fig. 1, showing the members locking the table top to the supporting base, the locking members being disengaged from the table top.

50 Fig. 4 is a view similar to Fig. 3 show-

ing the locking members in engagement with the table top, and,

Fig. 5 is a detail perspective view of one 55 of the locking members detached from the supporting base.

Referring more in detail to the accompanying drawing, the reference numeral 10 designates the supporting base of a ship's 60 table, the same being of hollow construction as illustrated in Fig. 1 and outwardly flaring at its lower end to provide a supporting base flange 11 resting upon the deck floor 12 and if desired, may be secured 65 thereto in any manner. The supporting base 10 is of circular construction and has the upper end 13 thereof cut-away upon its inner edge, as clearly shown in Fig. 1, to provide a plurality of spaced ball sockets 70 14 for the reception of anti-friction balls 15, the same being retained in position by the overlying collar 16 mounted upon the upper end of the base 10 and secured thereto as by fastening members 17.

The table top includes the flat section 18 having a central depending annular rib 19 adapted to be supported by and connected to the annular flange 20 upon the upper edge of the bowl-shaped member 21 by the 80 fastening members 22. The outer sides of the bowl-shaped member 21 is provided with a plurality of spaced grooves 23 adapted to receive the ball bearings 15 and be supported thereby in a substantially universal manner as shown in Fig. 1, rotary motion of the table top 18 with respect to the supporting base 10 being prevented by the ball and socket arrangement as shown in Fig. 2. A pendant weight 24 is connected 85

as at 25 to the lower end of the bowl-shaped member 21 and said pendant weight is contained within the hollow supporting base 10, being entirely hidden from view and adapted to maintain the table top 18 in a 90 horizontal position at all times regardless of the change of position of the ship's deck 12. When it is desired to hold the table top 18 locked or immovable with respect to the supporting base 10, the locking bars 26 are 95 employed, the same being slidable through recesses 27 formed in substantially diametrically opposite sides of the upper end of the supporting base 10. Each locking bar 26

75

95

100

includes an operating handle 28 having a side lug 29 adapted to be positioned in selective sockets 30 formed in one side wall of the slots 27, there being provided expansion 5 springs 31 fixed to the opposite sides of the slots 27 and freely engaging the rear faces of the locking bars 26 so that the locking bars may be moved to the dotted line position shown in Fig. 3 and be moved inwardly and 10 outwardly of the slot with the engaging ends of the springs wiping thereover and retaining the locking bars in the adjusted position. The inner end of each locking bar has a head 32 provided with a terminal rectangular socket 33 that is adapted to move into locking engagement with the rectangular portion 34 of the pendant weight 24, and as shown in Fig. 2, two locking bars 26 being employed, one is located a slight distance 15 above the other so as to permit the same to lie in overlapped relations when engaging the member 34 as shown in Fig. 4. In this latter position, the lateral lug 29 is located within the inwardly positioned recess 30 and retained in such position by 20 the engaging springs 31.

From the above detailed description of this invention, it is thought that the construction and operation thereof will be readily apparent, it being noted that when a ship provided with this table is rolling caused by high seas, the locking bars 26 may be disengaged from the rectangular portion 34 of the pendant weight 24 so as to render 30 the weight operative to cause the table top 18 to assume a horizontal position at all times regardless of the relative position of the deck portion 12. As above described, the table top may be locked immovable with 35 respect to the supporting base 10 for shifting the locking bars 26 carried by the supporting base into operative engagement with the pendant weight 24 to hold the same in the position as indicated by Fig. 4.

45 What I claim as new is:—

1. A ship's table embodying a hollow supporting base, ball bearings positioned at the upper end thereof, a table top carrying a centrally-disposed depending bowl-shaped 50 member having vertical grooves receiving

said balls and supported thereby, a pendant weight centrally carried by the bowl-shaped member and located within said hollow base, and locking bars carried by the base adapted to move transversely thereof to engage said table top to hold the same fixed relative to the supporting base. 55

2. A ship's table embodying a hollow supporting base, ball bearings positioned at the upper end thereof, a table top carrying a centrally-disposed depending bowl-shaped member having vertical grooves receiving said balls and supported thereby, a pendant weight centrally carried by the bowl-shaped member and located within said hollow base, 60 and tensioned locking bars slidably mounted transversely of said base adapted to engage said pendant weight to hold the table top immovable relative to the supporting base. 65

3. A ship's table embodying a hollow supporting base, ball bearings positioned at the upper end thereof, a table top carrying a centrally-disposed depending bowl-shaped member having vertical grooves receiving said balls and supported thereby, a pendant weight centrally carried by the bowl-shaped member and located within said hollow base, the said base having substantially diametrically-opposite slots therein, locking bars positioned in said slots, springs arranged in 70 said slots adapted to engage said locking bars to hold the same in adjusted positions, and co-operative means carried by said base and locking bars adapted to prevent sliding movement thereof, the said locking means 75 being moved into engagement with said pendant weight. 85

4. A ship's table embodying a supporting base, a table top movably supported thereby, a pendant weight carried by the table top, 90 the said base having oppositely disposed openings having sockets in one wall thereof, locking arms having pins positioned in said openings with the pins positioned in said sockets, springs engaging said arms, and forks formed at the inner ends of said arms adapted to engage the shank of the depending weight to hold the table top immovable. 95

In testimony whereof I affix my signature.
FRANK ZAGMESTER.
